UNITED STATES PATENT OFFICE.

WARD B. STORY, OF NEW YORK, N. Y., ASSIGNOR TO AMERICAN ASSEMBLING MACHINE COMPANY, A CORPORATION OF DELAWARE.

OPENING DEVICE.

1,202,914.

Specification of Letters Patent. Patented Oct. 31, 1916.

Application filed November 18, 1915. Serial No. 62,098.

To all whom it may concern:

Be it known that I, WARD B. STORY, a citizen of the United States, and a resident of the borough of Manhattan, in the county 5 of New York, city and State of New York, have invented certain new and useful Improvements in Opening Devices, of which the following is a specification.

This invention relates to improvements in 10 opening devices for folded paper sections and is particularly adapted for use in connection with newspaper "stuffing" machines of the type shown in the patent to Claud D. Curry #1,117,000, Nov. 10, 1914.

15 A folded paper section might be said to comprise two plies, each ply in turn consisting of a plurality of sheets or leaves, and difficulty has heretofore been experienced in insuring the opening of the folded paper 20 section between the two plies, and in guarding against the opening of the paper section between individual sheets of one or the other ply. An object of this invention is to provide improved means for performing the 25 opening function to invariably open the paper section between the two plies.

Briefly stated one feature of the invention comprises: devices for initially opening the 30 plies of a folded paper section and for thereafter completing the opening thereof, both the devices for initially opening the paper section and for completing the opening of the section being mounted on the two members which are movable to and from 35 with relation to each other and to an intermediate folded paper section. By thus mounting the opening devices a separate and distinct structural unit for completing the opening of the paper sections, which is 40 characteristic of prior devices of this nature, is rendered unnecessary.

In the accompanying drawings I have 45 illustrated a preferred embodiment of the invention but wish it understood that various changes and modifications may be made therein without departing from the spirit and scope of the invention.

In the drawings: Figure 1 is a transverse vertical sectional view of the device embodying the invention. Fig. 2 is a section taken along the line 2—2 of Fig. 1, and looking toward the left. Fig. 3 is a view similar 50 to Fig. 2 but taken along the line 3—3 of

Fig. 1. Fig. 4 is a sectional view taken in different angles to the views shown in Figs. 55 2 and 3 and taken along the irregular line 4—4 of Fig. 3 looking in the direction of the arrows. Fig. 5 is a horizontal sectional view taken along the line 5—5 of Fig. 4. Fig. 6 is a vertical transverse sectional view 60 similar to Fig. 1 but with some of the parts shown in Fig. 1 omitted to more clearly show the arrangement of other parts.

A feature of the mechanism for initially opening the folded paper section consists 65 in providing members for engaging both outer sides of the folded paper section in two places and in thereafter buckling one ply of the paper section.

That portion of the device which is used 70 in initially opening the folded paper sections preferably takes the form of the buckling member shown at 5 and pivotally mounted on the head 4 which is rigidly attached to the movable member 2. Holding 75 devices 8 and 9 and a cam 11 mounted on the head 3, carried by the movable member 1, and holding lug 10, mounted on the same support that carries the buckling member, cooperate with the buckling member in the 80 performance of its function. These devices are carried to and from each other by the movement of the members 1 and 2, the members in their opened position receiving the folded paper section and as they approach 85 their closed position, with the paper section supported intermediate the devices carried by the heads 3 and 4, bring about the engagement of parts which causes the buckling member to rock on its support and to thereby 90 buckle the ply of the folded paper section with which it engages.

Motion is given to the movable members 1 and 2 through the movement of the arm 12 which is driven from some suitable source 95 of power. The arm 12 is rigidly connected with the movable member 1 which is mounted to rock freely on the rotatable shaft 6. Through the intermeshing gear segments 13 and 14 carried by movable members 1 and 2 100 motion is conveyed to movable member 2 mounted on rock shaft 7 so that the movable members operate in unison.

Another feature of the invention consists 105 in the provision of means for initially opening the plies of a folded paper section, the

moving of separate fingers lengthwise in between the partly separated plies, and for moving the fingers transversely away from each other to complete the opening of the 5 paper section.

That portion of the device which constitutes the means for completing the separation of the plies of the paper section preferably consists of the fingers 37 and 38 which 10 are movably mounted on the heads 3 and 4. These fingers are constructed to be moved lengthwise between the plies 39 and 40 of the partially opened paper section and to then be moved transversely away from each other 15 by the movement of the movable members to complete the opening of the paper section.

The fingers 37 and 38 are carried by supporting members 41 and 42 which are in turn carried by the guide rods 43 and 44 20 mounted to slide in the hollow guide members 45 and 46 mounted in the fixed brackets 47, 48, 49 and 50 mounted on the heads 3 and 4. The flanged rollers 51 and 52 traveling on the guideways 53 and 54, extending 25 from the heads 3 and 4 respectively, serve to hold the fingers 37 and 38 in their proper circumferential relation with respect to the guide rods 43 and 44.

In order to reciprocate the fingers 37 and 30 38 lengthwise the sliding carriage 55 is provided which is mounted to reciprocate along the stationary shafts 25 and 26. Through a link 56 this carriage is connected to a lever 57 fulcrumed to the fixed part 58 and provided with a cam roll 59 which co-operates 35 with a cam 60. This cam 60 is secured to the rotating shaft 6 and operates to rock the lever and thus reciprocate the carriage 55 to give motion to the fingers 37 and 38 at 40 the proper point in the operation of the machine.

The sliding carriage 55 is operably connected to the members on which the fingers are supported by means of two grooves 61 45 and 62 arranged transversely of the path of movement of the sliding carriage and corresponding rollers 63 and 64 mounted on the finger supports and engaging the grooves. By this construction it is possible to preserve 50 the operative connection between the sliding carriage and the fingers whatever the relative lateral position of the members and the fingers carried thereby may be.

The specific structure of the preferred devices for initially opening a folded paper 55 section, and which have already been generally discussed, will now be specifically described.

Mounted on the hollow guide member 45 60 which as has already been pointed out is carried by the fixed brackets 47 and 48 on the head 3, best shown in Figs. 2 and 5, are two yielding backing, or abutment, members 65 and 66. The member 65 extends 65 downwardly and is provided with the con-

tact portion 9 adapted to engage a side of the paper section. A spring pressed plunger 68 working in a casing 69 constantly presses against a shoulder 70 on the abutment member and tends to hold the contact 70 portion in its outermost position. A stop 71 on the opposite side of the pivot engages the adjustable screw 72 to limit the spring impelled movement of the abutment member. 75

The remaining abutment member 66 extends upwardly from the support 45 and carries the contact member 8 pivoted to swing on an axis approximately at right angles to the support 45 to provide a universal motion therefor. The purpose of this is to 80 enable the member 8 to adapt itself to varying surfaces to thereby provide the same pressure at all points along the face of the buckling member 5. A spring pressed plunger 74 acts to hold the abutment member 66 85 in its outermost position. A threaded follower 75 is used to adjust the degree of pressure furnished by the spring. A stop 76 on the under side of the pivot, (see Fig. 2) engages the face of the head 3 to limit the 90 spring impelled movement of the member 66. Also carried by the abutment member 66 is a clamping member 77 actuated by the spring plunger 74 in the opening movement 95 of the members 1 and 2 to clamp the paper ply 39 against the finger 37.

Mounted on the head 4 is the fixed holding member 10 arranged to co-operate with the contact portion 9 of the abutment member 65 to hold a folded paper section. The buckling member 5, already mentioned, is pivoted in fixed brackets 79 and 80 carried by the head 4. That portion of the buckling member which is arranged to directly engage the paper has a surface adapted to offer a high degree of frictional resistance to the sliding of paper along such surface. A clamping element 81 carried by the buckling member receives the pressure of the spring pressed plunger 82 and serves a purpose similar to that of the corresponding clamping element 77 carried by the abutment member 66. In the outermost position of the clamping element 81 the contact portion 83 thereof acts to clamp the paper ply 40 against the finger 38. To limit the outward movement of the clamping member 81 and the upward movement of the buckling member 5 the stop 84 is provided which abuts against the head 4 to limit such movement. 105

Carried by the buckling member 5 is the roller 85 and adjustably mounted on the head 3 is the cam 11 arranged to depress the roller 85 and thereby rock the buckling member on its pivot as the members 9 and 8 carried by the head 3 engage the buckling member 5 and the fixed holding member 10. As has been already pointed out the abutment members carried by the head 3 are adapted to yield and it is during this yield- 110 115 120 125 130

ing motion that begins with the first engagement of the opposing members that the interposed paper section is buckled by the operation of the buckling member 5.

5 In order to support the folded paper section while the opening mechanism is advancing to perform its function, supporting arms 15 and 16 mounted to rock on shafts 17 and 18 and adapted to be operated at the proper time through an arm 19 and rod 20, are provided. Intermeshing gear segments 21 and 22 similar to gear segments 13 and 14 are used to convey motion from arm 16 to arm 15 and insure the movement of the supporting arms in unison.

Another pair of arms 23 and 24 are mounted to rock on shafts 25 and 26 and are adapted to be operated by an arm 27 and a rod 28. Gear segments 29 and 30 are used to convey motion from arm 24 to arm 23 when the rod 28 is operated in proper timed relation to the movable parts with which it coöperates. The arms 23 and 24 carry ejecting rolls 31 and 32. The roll 31 is constantly rotated through gears 33 and 34 which are in turn driven from the moving part 36 through a flexible shaft 35.

In the operation of the device a folded paper section is passed downwardly between the guide members 87 and 88 with the fold lowermost. At this point in the operation of the device, the members 1 and 2 are in their opened position, the fingers 37 and 38 are retracted and the supporting members 15 and 16 are in closed, or supporting position. The folded paper section passes down to and rests upon the supporting members 15 and 16.

With the folded paper section in position to be operated upon, the arm 12 is raised to move the members 1 and 2, through the action of the gear segments 13 and 14 to closed position. As the members approach each other, the folded paper section is held between the fixed lug or abutment member 10 and the yielding abutment member 9 at one place, and between the yielding abutment member 8 and the buckling member 5 at another. The pivoted abutment members carried by the face plate 3 are adapted to yield after the first engagement takes place and during the yielding movement the cam roll 85 on the buckling member 5 is engaged by the cam 11. This engagement causes the buckling member to turn on its axis and since the friction face of the buckling member is pressed against a ply, or member of the folded paper section, movement is given to a portion of the paper along the surface planes thereof. Since the paper

60 is firmly held between the abutment members 9 and 10, the portion of the paper in contact with the buckling member 5 is buckled, so as to separate the two members of the folded paper section intermediate the two places at which the paper is held. In

order to insure the initial opening of the folded paper section and to avoid the tearing of the upper edges of the paper section the movement of the buckling member 5 is made in a direction oblique to the edges of the paper section.

70 In order to facilitate the initial opening of the folded paper section, the abutment member 10 is arranged to project outwardly from the head 4 to a greater extent than does the buckling member 5. By this construction that part of the folded paper section which is held between the buckling member 5 and the holding device 8, is moved laterally out of alinement with that part of the paper section between and below the members 9 and 10. It will be evident that this initial distortion or bending of that part of the paper section between the two engaged portions will facilitate the further 80 distortion or buckling of the right-hand ply, since the buckling member will be relieved of the burden of moving the ply directly in its own plane against the relatively large resistance which would be thereby encountered.

90 When this initial separation or opening of the folded paper section has been effected the cam 60 operates to give movement to the lever 57 through engagement of the cam roll 59 thereon with the cam 60. The movement 95 of this lever through the link connection 56 reciprocates the carriage 55 along the guide shafts 25 and 26. Through the engagement of the rollers 64 and 65 with the guiding grooves 61 and 62, motion is conveyed to the

100 fingers 37 and 38 which are thereby projected into the space which has been provided between the members of the paper section by the action of the buckling member 5. When the fingers have been placed in this 105 position the direction of movement of the arm 12 is reversed and an opening movement of the members 1 and 2 begun. In the initial part of this opening movement the spring plungers 74 and 82 act on the clamping members 77 and 81 respectively to clamp the members of the partially unfolded paper section firmly against the respective fingers 37 and 38. Accordingly in the further opening movement of the members 1 and 2 the 110 portions of the paper section are firmly held so that their continued opening movement is insured.

115 During the opening movement of the members 1 and 2 the fingers 37 and 38 are retained in holding position by the action of the cam 60 which is so constructed as to prevent movement of the lever 57 during this portion of the operation of the device.

120 The fingers are caused to be carried laterally with the members 1 and 2 and with relation to the carriage 55 without destroying their operative connection with the carriage 55 by means of the grooves 61 and 62 provided on said carriage.

- As the members 1 and 2 move to opened position, shown in dotted lines in Fig. 5, an insert, which may be another folded paper section, passes down through the 5 guide members 87 and 88 into position in the now opened paper section. When the insert has reached its position, the cam 60 operates to withdraw the fingers 37 and 38 from their paper engaging position, thus 10 releasing the plies of the paper section. Coincident with this releasing movement the rods 20 and 28 are operated to separate the supporting members 15 and 16 and to move the ejecting rollers 31 and 32 into engagement with the paper section whereupon the paper section is discharged downwardly between the guide members 89 and 90 and out between the discharging rollers 91 and 92.
- 15 It is to be noted that in the initial opening of the paper section the action of the buckling member in frictionally gripping and buckling a ply of the paper section is such that all the leaves constituting the ply are moved with relation to the leaves making up the remaining ply which results in a more certain separation of the plies along the proper dividing line. Also the action of the devices for completing the opening of 20 the paper section is an improvement over corresponding devices shown in the art in that the plies of the paper section are positively gripped and moved to their separated position directly by the swinging movement 25 of the main operating members.
- 30 What is claimed, is:
1. An opening device for a paper inserting machine comprising: means movable to and from with relation to each other and to an intermediate folded paper section including devices for initially opening the folded paper section, said means also including other devices for completing the opening of the partially opened paper section.
  - 40 2. An opening device for a paper inserting machine comprising: devices for initially separating the plies of a folded paper section and other devices for thereafter completing the separation of said plies, and means for carrying said first-named and said second-named devices consisting of two members movable to and from with relation to each other and to an intermediate folded paper section.
  - 45 3. An opening device for a paper inserting machine comprising: means movable to and from with relation to each other and to an intermediate folded paper section including devices for initially opening said folded paper section as said members move toward each other; and means carried by said movable means to complete the opening of the partially opened paper section.
  - 50 4. An opening device for a paper inserting machine comprising: means movable to and from with relation to each other and to an intermediate folded paper section including devices for initially opening said folded paper section as said members move toward each other; and means carried by said movable means to complete the opening of the partially opened paper section.
  - 55 5. An opening device for a paper inserting machine comprising: means movable to and from with relation to each other and to an intermediate folded paper section including devices for initially opening said folded paper section as said members move toward each other; and means carried by said movable means to complete the opening of the partially opened paper section.
  - 60 6. An opening device for a paper inserting machine comprising: means movable to and from with relation to each other and to an intermediate folded paper section including devices for initially opening said folded paper section as said members move toward each other; and means carried by said movable means to complete the opening of the partially opened paper section.
  - 65 7. An opening device for a paper inserting machine comprising: means movable to and from with relation to each other and to an intermediate folded paper section including devices for initially opening said folded paper section as said members move toward each other; and means carried by said movable means to complete the opening of the partially opened paper section.

and from with relation to each other and with relation to an intermediate folded paper section including devices for initially opening said folded paper section as said members approach each other; and means 70 carried by said movable means to complete the opening of the partially opened paper section as the members move away from each other.

5. An opening device for a paper inserting machine comprising: members movable to and from with relation to each other and to an intermediate folded paper section; devices carried by said members and actuated by said members as they move toward 75 each other to initially open said folded paper section, and means for completing the opening of the partially opened paper section.

6. An opening device for a paper inserting machine comprising: members movable to and from with relation to each other and to an intermediate folded paper section, devices carried by said members and actuated by said members as they move toward each 80 other to initially open said folded paper section, and devices carried by said members to complete the opening of the partially opened paper section as the members move 85 away from each other.

7. An opening device for a paper inserting machine comprising: members movable to and from with relation to each other and to an intermediate folded paper section, one of said members including a device for initially opening said folded paper section, a device mounted on the other member for actuating said opening device as the members approach each other; and means to 90 complete the opening of the partially 95 opened paper section.

8. An opening device for a paper inserting machine comprising: members movable to and from with relation to each other and to an intermediate folded paper section, one of said members including a device for initially opening said folded paper section, a device mounted on the other member for actuating said opening device as the members approach each other, and means carried by 100 said members to complete the opening of the partially opened paper section as the members move away from each other.

9. An opening device comprising: means 105 for initially separating the plies of a folded paper section including members for engaging both outer sides of the folded paper section in two places and for thereafter buckling one ply, and means for completing the 110 separation of the plies.

10. An opening device comprising: means 115 for initially separating the plies of a folded paper section including members for engaging both outer sides of the folded paper section in two places, and for thereafter buckling one ply, and means for completing the 120 separation of the plies.

11. An opening device comprising: means 125 for initially separating the plies of a folded paper section including members for engaging both outer sides of the folded paper section in two places, and for thereafter buckling one ply, and means for completing the 130 separation of the plies.

kling one ply intermediate the two places of engagement, and means for completing the separation of the plies.

11. An opening device comprising: means for initially separating the plies of a folded paper section including two sets of members for engaging both outer sides of the folded paper section in two places in the plane of a line drawn from the folded edge to the free edges opposite the latter, and for thereafter buckling one ply, and means for completing the separation of the plies.

12. An opening device comprising: means for initially separating the plies of a folded paper section including members for engaging both outer sides of the folded paper section in two places, one of said members being movable, and means for moving said member to buckle one of said plies, and means for completing the separation of the plies.

13. An opening device comprising: means for initially separating the plies of a folded paper section including members for engaging both outer sides of the folded paper section, one of said members being movable obliquely toward the remaining engaged portion of the paper section, and means for moving said member to buckle one of said plies, and means for completing the separation of the plies.

14. An opening device comprising: members movable to and from with relation to each other and to an intermediate folded paper section including devices for engaging both outer sides of the folded paper section in two places, one of said devices being movable and a device to buckle one ply of the folded paper section to initially open said paper section, and means to complete the opening of said paper section.

15. An opening device comprising: members movable to and from with relation to each other and to an intermediate folded paper section including devices for engaging both outer sides of the folded paper section in two places, one of said devices being movable, and a device mounted on the other member for moving said movable device to buckle one ply of the folded paper section to initially open said paper section, and means carried by said members to complete the opening of the paper section as the members move away from each other.

16. An opening device for a paper inserting machine comprising: members movable to and from with relation to each other and to an intermediate folded paper section, yielding devices carried by one of said members, devices carried by the other member and constructed and arranged to coöperate with the yielding devices on the other member to engage the intermediate folded paper section in two places one of the second named devices being movable to buckle a ply of the

folded paper section to initially separate said plies, means to actuate said buckling device, and means to complete the opening of said paper section.

17. An opening device for a paper inserting machine comprising: members movable to and from with relation to each other and to an intermediate folded paper section, yielding devices carried by one of said members, devices carried by the other member and constructed and arranged to coöperate with the yielding devices on the other member to engage the intermediate folded paper section in two places, one of the second named devices being movable to buckle a ply of the folded paper section to initially separate said plies, means carried by the other member to actuate said buckling device; and means to complete the opening of said paper section as the members move away from each other.

18. An opening device comprising: means for initially separating the plies of a folded paper section, two sets of complementary members, the members of each set constructed and arranged to grasp a ply on opposite sides thereof, and means for moving said sets of members away from each other to complete the separation of the plies of the section.

19. An opening device comprising: means movable to and from with relation to each other and to an intermediate folded paper section including members for initially opening said folded paper section, and two sets of complementary members, the members of each set constructed and arranged to grasp a ply on opposite sides thereof to complete the opening of the partially opened paper section as the means are moved away from each other.

20. An opening device comprising: means for initially separating the plies of a folded paper section, separating fingers movable lengthwise in between the partly separated plies, and means for moving said fingers transversely away from each other to complete the separation of the plies.

21. An opening device comprising: members movable to and from with relation to each other and to an intermediate folded paper section, devices for initially separating the plies of a folded paper section, and separating fingers carried by said members and movable lengthwise in between the partly separated plies to complete the separation of the plies as the members move away from each other.

22. An opening device for a paper inserting machine comprising: members movable to and from with relation to each other and to an intermediate folded paper section, said members including devices for initially opening said paper section, and devices carried by said members for grasping the partially

opened plies of said paper section to complete the separation thereof as the members move away from each other.

23. An opening device for a paper inserting machine comprising: members movable to and from with relation to each other and to said folded paper section, said members including devices for initially opening said paper section, holding devices movably carried by said members, and devices for moving said holding devices to a position between the plies of said partially opened paper section to complete the opening thereof as the members move away from each other.

24. An opening device for a paper inserting machine comprising: members movable to and from with relation to each other and to an intermediate folded paper section, said members including devices for initially opening said paper section, holding fingers movably carried by said members, devices for moving said holding devices to a position between the plies of said partially opened paper section, and clamping devices on said members arranged to coöperate with said holding fingers to complete the opening of said paper section as the members move away from each other.

25. An opening device for a paper inserting machine comprising: means for initially opening a folded paper section including devices for holding said folded paper section while said paper section is being initially opened, clamping devices to grasp the initially separated plies of the paper section, said holding devices operating to hold said clamping devices inoperative when said holding devices are in holding position, means for actuating said clamping devices when said holding devices are not in holding position, and means for moving said clamping devices to complete the opening of the paper section.

26. An opening device for a paper inserting machine comprising: members movable to and from with relation to each other and to an intermediate folded paper section, holding devices carried by one of said members, holding devices carried by the other member and arranged to coöperate with the holding devices on the first-named member to hold the intermediate folded paper section, one of the second-named devices being operable to buckle a ply of the folded paper section to initially separate the plies, a clamping device carried by the buckling device, a clamping device carried by the corresponding device on the first-named member, said clamping devices operating to grasp the initially separated plies of the paper section to complete the separation thereof as the members move away from each other.

27. An opening device for a paper inserting machine comprising: members movable to and from with relation to each other and

to an intermediate folded paper section, holding devices carried by one of said members, holding devices carried by the other member and arranged to coöperate with the holding devices on the first-named member to hold the intermediate folded paper section, one of the second-named devices being operable to buckle a ply of the folded paper section to initially separate the plies, a clamping device carried by the buckling device, a clamping device carried by the corresponding device on the first-named member, spring means tending to render said clamping means operative, said clamping means being held inoperative by said holding devices when said holding devices are in holding position, said clamping devices operating to grasp the initially separated plies of the folded paper section to complete the separation thereof as the members move away from each other.

28. An opening device for a paper inserting machine comprising: members movable to and from with relation to each other and to an intermediate folded paper section, said members including devices for initially opening said paper section, a finger reciprocably mounted on each of said members, devices for reciprocating said fingers to project said fingers between the partially separated plies of said paper section, spring pressed clamping devices carried by said members and held inoperative by said members when said members are at a minimum distance apart, said clamping devices being constructed to be released in the initial parting movement of said members to clamp the plies of said partially opened paper section against said fingers whereby as the members are moved apart the opening of the paper section will be completed.

29. An opening device for a paper inserting machine comprising: members movable to and from with relation to each other and to an intermediate folded paper section, devices for initially opening the folded paper section, fingers movable with the members for completing the opening of the partially opened paper section, and means for reciprocating the fingers at right angles to the path of movement of the movable members irrespective of the position of the movable members.

30. An opening device comprising: jaws movable to and from with relation to an intermediate folded paper section, devices for initially opening said folded paper section when the jaws are in closed position, separating fingers reciprocable between said jaws, and means for reciprocating said fingers into a position between the plies of the paper section when the jaws are closed.

31. An opening device comprising: members movable to and from with relation to each other and to an intermediate folded

paper section, said members including devices for initially opening said folded paper section, holding fingers reciprocably mounted on said members to travel across the 5 path of movement of said members, means for moving said fingers, and means for maintaining the operative connection between said fingers and said means in the lateral movement of said fingers with relation 10 to said means.

32. An opening device comprising: members movable to and from with relation to each other and to an intermediate folded paper section, separating fingers mounted 15 on said movable members and constructed and arranged to be reciprocated across the path of movement of said movable members, a reciprocating carriage with transverse grooves arranged to reciprocate said fingers, said fingers having extensions extending into said transverse grooves whereby the carriage is adapted to reciprocate the 20 fingers in any position of the movable members.

33. An opening device for a paper inserting machine comprising: means for initially distorting the plies of a folded paper section, means for thereafter buckling one of said distorted plies to partially open the 25 paper section, and means for completing the opening of the partially opened paper section.

34. An opening device for a paper in-

serting machine comprising: members movable to and from with relation to each other and to an intermediate folded paper section including devices for initially distorting said plies and thereafter buckling one of said distorted plies to partially open said folded paper section as said members move 35 toward each other, and means to complete the opening of the partially opened paper section.

35. An opening device comprising: means for initially separating the plies of a folded paper section including members for engaging both outer sides of the folded paper section in two places and distorting said paper section, means for buckling one of said distorted plies, and means for completing 40 the separation of the plies.

36. An opening device for a paper inserting machine comprising: means movable to and from with relation to each other and to an intermediate folded paper section including devices for distorting said paper section, devices for buckling one ply of the distorted section to initially open the folded paper section, and devices for completing the opening of the partially opened paper 50 section.

Signed at New York city, in the county of New York and State of New York, this 17th day of November, A. D. 1915.
